COMBINED MOUNTING BRACKET AND REEL FOR A SAFETY BELT FOR AUTOMOBILES

Eugene F. Busch, R.F.D. 2, Litchfield, Conn.

Filed July 27, 1964, Ser. No. 81,034

Term of patent 14 years

(Cl. D41—1)

Fig.1

Fig.3

FIG. 1 is a side elevational view of a combined mounting bracket and reel for safety belt for automobiles showing my new design;

FIG. 2 is a front elevational view; and

FIG. 3 is a rear perspective view.

This application is a continuation-in-part of Serial No. D. 77,926, filed by me Dec. 26, 1963 and now abandoned.

I claim:

The ornamental design for a combined mounting bracket and reel for a safety belt for automobiles, as shown.
